[57] CLAIM

The ornamental design for a bottle, substantially as shown and described.

DESCRIPTION

FIG. 1 is an elevational view of a bottle showing my new design;

FIG. 2 is a top plan view; and

FIG. 3 is a bottom plan view.

The bottle shown in FIG. 1 is symmetrical and is the same in appearance on its other sides as the side shown.

FIG. 1

FIG. 2

FIG. 3
